UNITED STATES PATENT OFFICE.

LUKE MOONEY, OF BAYONNE, NEW JERSEY.

PROCESS OF AND APPARATUS FOR REMOVING DEPOSITS FROM CRUDE-OIL STILLS.

1,174,888.

Specification of Letters Patent.

Patented Mar. 7, 1916.

Application filed September 16, 1915. Serial No. 51,046.

To all whom it may concern:

Be it known that I, LUKE MOONEY, a citizen of the United States, residing at Bayonne, in the county of Hudson and State of New Jersey, have invented certain new and useful Improvements in Processes of and Apparatus for Removing Deposits from Crude-Oil Stills; and I do hereby declare the following to be a full, clear, and exact 10 description of the invention, such as will enable others skilled in the art to which it appertains to make and use the same.

This invention relates to a method of and an apparatus for removing coke from tar 15 stills and has for its object to provide a method and an apparatus of the character described which will be certain in action and more efficient in operation than those heretofore proposed.

20 With these and other objects in view the invention consists in the steps constituting the method and in the novel details of construction and combination of parts constituting the apparatus, all as will be more 25 fully hereinafter disclosed and particularly pointed out in the claims.

Referring to the accompanying drawings forming a part of this specification in which like numerals designate like parts in all the 30 views,—Figure 1 is a diagrammatic longitudinal sectional view on the line 1—1 of Fig. 2 of a still equipped with the invention; Fig. 2 is a sectional view taken on the line 2—2 of Fig. 1 looking in the direction of the arrows; and Fig. 3 is detail view partly in section of the chain and pipe sections employed 35 in connection with the invention.

In the operation of an oil refinery at the present time, it is usual to distil a large percentage of the crude oil until coke is produced in the still, or stated in other words, the still is usually fired until the volatile products have been driven off and coke to the depth of say from six to fourteen inches 40 depending on the character of the crude oil, is formed on the bottom of the still. This deposit becomes hard and very difficult to remove. However when it is to be removed fire is withdrawn from the still, the coke is 45 allowed to harden, and steam is turned in, until the still contains sufficient steam to prevent the ignition of the gases upon the entrance of air, whereupon the man-heads of the still are taken off and the still thus is 50 opened to the atmosphere. The still is now allowed to cool off until the temperature is 55 sufficiently low to permit a man to enter the still, and by the aid of an iron bar sharpened at one end and known as a "spud" to loosen up as much of the coke as it is possible to do 60 during the short period he is able to stand the gases and the high temperature on the inside of said still. As good practice requires as many runs as possible to be obtained from the still during a year, it is necessary for the 65 men to enter the still when the temperature ranges as high as from 200° F. or higher. In order to protect the men from these abnormal high temperatures they are clad in additional clothing, their eyes and faces are covered, their feet are protected by heavy clogs, their hands are protected with canvas and usually their knees are provided with an extra thickness of canvas. Clad in this way 70 an experienced still cleaner may work in 75 such a high temperature for say three or four minutes at a time, and sometimes even as long as six minutes as it is possible to withstand these high temperatures for these periods by reason of the fact that the interior of the still is free from humidity, while on the other hand if the atmosphere in the still contained any substantial amount of moisture it would be impossible for a man to enter and stay any such lengths of time 80 85 at all. After the coke is thus broken up with an iron spud as above mentioned, it is shoveled out through a man hole on the end of the still, and as these stills are often forty-two feet in length it will be seen that 90 the job of disintegrating and shoveling out as much as fourteen inches of coke from a still of this character and under the conditions stated is a most difficult one. In order 95 to enable men to remain longer in a still it is not unusual at present to have air forced 100 therein, but the men generally object to the air on account of the discomfort caused by its humidity, and therefore as a rule the men prefer to work as long as possible under the ordinary conditions and then to take a long rest after each short period of work.

In order to overcome the above objections both as to the loss of time and to the great expense involved in removing coke from stills, the invention now about to be disclosed has been provided.

Referring to the accompanying drawings, 1 indicates any suitable still, 2, 3, 4, 5 and 6 any suitable openings therein provided with closures not shown, and 7 is a layer of coke or other deposit usually found in the bottom 110

of such stills after the crude oil has been subjected to the usual heating operation. 8 represents a chain preferably provided at convenient intervals with short sections 5 of pipe or bars 9, which chain and sections are placed in the still before the oil is run thereinto and which is allowed to occupy a position on the bottom of the still as is shown in Fig. 1. There are preferably employed 10 a plurality of chains 8, such as is illustrated in Fig. 2, each provided with the sectional members 9, and on the interior of the heads 10 of the still there are preferably provided hooks 11 or other means by which 15 the ends 12 of the chains 8 may be supported during the distilling operation. The still 1 being thus equipped with one or more chains 8 and the ends 12 thereof being supported on the interior of the still, as by the 20 hooks 11, the crude oil is admitted to the interior of the still, and the distilling operation is proceeded with as usual. After the coke 7 or other deposit is formed, and it is desired to remove the same, the men may 25 reach into the still, or they may even enter the same in the manner above disclosed and the ends 12 of the chains 8 be caused to engage with hooks 14 carried by the wire ropes or cables 15, passing over the windlass 30 or other hoisting apparatus 16, which may be conveniently supported as by the members 17 on the cross beams 18, spanning the two openings 4 and 6 of the still, these beams 18 being themselves conveniently 35 supported by the uprights 19 leading to the ground or other firm support. The ends 12 of the chains being thus quickly secured to the hooks 14 of the cables 15 power is then immediately applied to the said cables 15 40 by any suitable means as for example by the hand operated windlasses 20 attached to the drums or other hoisting apparatus 16, and the said chains 8, together with their sectional members 9 are lifted from the 45 bottom of the still, whereupon the coke 7 is broken up into pieces of convenient size depending upon the spaced relation of the said members 9 and also upon the spaced relation existing between the different sets of chains 8. It is necessary to 50 see that sufficient steam is turned into the still during the breaking up process to prevent the coke from taking fire and to carry off through the man-heads the excessive 55 heat suddenly released. The breaking up of the coke in the manner disclosed permits the great heat contained therein to quickly dissipate and therefore renders it much easier for the men to enter the still than 60 would be the case if the coke remains intact. The coke 7 being thus broken up, it is a comparatively easy matter for men protected as above to enter the still and to throw said pieces bodily upon any convenient conveyor 65 mechanism such as 25 which has been

previously introduced into the still as through the opening 2 for example. Any suitable form of conveyer may be utilized and in the conventional form shown I have illustrated the supporting members 26 and an endless belt 27, operated from a source of power not shown. Further the heat being thus dissipated by the breaking up of the coke and the men being more comfortable in the still than they otherwise would be, 75 cold air is next forced into the still so as to enable the men to stay longer therein. In order to avoid the discomfort produced by any moisture the air may contain, the said moisture is preferably frozen out of the air 80 or the same is otherwise dried before being introduced into the still. Not only does the introduction of cold dried air into the still serve to reduce the initial temperature, but the dried air will absorb any moisture that might otherwise be in the still and thereby 85 still further remove the objections the men have to the introduction of air into the still. After the larger broken up particles of coke have been thus thrown onto the conveyer 90 and removed from the still, the men next proceed to dislodge any remaining portions of coke with their spuds as heretofore, and the said dislodged portions are further thrown onto the conveyer with the result 95 that a still of forty feet long may be completely cleaned with far more comfort to the men and in a far less time, when equipped with the above disclosed apparatus than it would be possible to do under the old system. 100

It is obvious that those skilled in the art may vary the details of construction, as well as the arrangement of parts and the mode of operation, without departing from the spirit of the invention, and therefore it is 105 not wished to be limited to the above disclosure except as may be required by the claims.

What is claimed is:

1. The process of loosening a portion of 110 a coke like deposit from the interior of an oil still, which consists in providing the bottom of said still while free from said deposit with a lifting means; causing said deposit to form above and cover a portion of said 115 lifting means; and then raising said lifting means to loosen a portion of said deposit from said still, substantially as described.

2. In an apparatus for loosening coke-like 120 deposits from the interior of an oil still the combination of means adapted to extend along the bottom of said still and to have said deposits cover the same when set; and means located outside of said still for raising said first named means and thereby 125 breaking up a portion of said deposits, substantially as described.

3. In an apparatus for removing coke like 130 deposits from an oil still the combination of a power exerting means located on the

outside of said still; flexible connections with said means adapted to extend along the bottom of said still to underlie said deposits when set, and to be raised up through the solid deposits to break up the same; and a conveyer means adapted to enter the still and receive the broken portions of said deposits, substantially as described.

4. In an apparatus for removing coke like deposits from an oil still the combination of a chain adapted to underlie the said deposits; and a hoisting means adapted to be connected with said chain and to force the same through the bodies of said deposits, thereby breaking up the same, substantially as described.

5. In an apparatus for removing coke like deposits from an oil still the combination of a chain adapted to underlie the said deposits; a hoisting means adapted to be connected with said chain and to force the same through the bodies of said deposits, thereby breaking up the same; sectional members attached to said chain to aid in the breaking

operation; and a conveyer adapted to receive the broken portions of said deposits, substantially as described.

6. The process of loosening a portion of a coke like deposit from the interior of an oil still, which consists in providing the bottom of said still, while free from said deposit, with a lifting means; causing said deposit to form above and cover a portion of said lifting means; raising said lifting means to loosen a portion of said deposit from said still; introducing cold air deprived of a portion of its moisture on the interior of said still; and then breaking up by hand from the inside of the still, other portions of said deposits, substantially as described.

In testimony whereof I affix my signature, in presence of two witnesses.
